UNITED STATES PATENT OFFICE.

CLEMENT C. McDONALD, OF CHENOA, ILLINOIS.

SIDEWALK.

1,089,380.

Specification of Letters Patent.

Patented Mar. 3, 1914.

Application filed April 28, 1913. Serial No. 764,200.

To all whom it may concern:

Be it known that I, CLEMENT C. McDONALD, a citizen of the United States, residing at Chenoa, in the county of McLean and 5 State of Illinois, have invented certain new and useful Improvements in Sidewalks, of which the following is a specification.

My invention relates to improvements in cement walks, and more particularly to that 10 class of walks which are constructed of slabs made of cement, concrete, or the like, the object being to embed tubing in the slabs as they are molded, so that as the slabs are laid they can be connected together by 15 means of dowel pins.

The invention consists of certain novel features of construction and combinations of parts which will be hereinafter described and pointed out in the claim.

20 In the accompanying drawings:—Figure 1 is a perspective view showing several slabs connected together. Fig. 2 is a longitudinal, horizontal, sectional view through the ends of two adjoining slabs. Fig. 3 is 25 a view of a modified form of slab partly broken away to disclose the connection of tubing.

A represents concrete or cement slabs and B the tubes which extend longitudinally 30 of the slabs. Dowel pins 1 are provided with an annular flange 2 which flange is received between the ends of the slabs, and the ends of the pins extend into the tubes of the adjacent slabs, the flanges preventing 35 the pins from ever becoming disengaged or passing into the tube of one of the slabs, thereby leaving the other slabs disengaged from the first flange. This connection forms a means of properly alining 40 the slabs in the laying of a walk. With this

connection the slabs can be easily disengaged and removed during excavating. In many instances it is necessary to excavate for the purpose of getting access to water and sewage pipes, and when this is done 45 with the use of cement or concrete walks, it is impossible to get all of the soil back beneath the cement or concrete walk, and eventually the walk will settle and crack and injure it beyond repair, whereas with 50 slabs of this character it can be removed and re-laid at any time.

In Fig. 3 I have disclosed a modified form in which tubing extends longitudinally and transversely of the slab, and at 55 their junctures the several tubes B are connected together by four-way couplings 3.

Having fully described my invention, what I claim and desire to secure by Letters Patent is:

In a sidewalk, the combination with a plurality of slabs having recesses in the ends thereof, of tubes embedded within the slabs having the outer ends thereof flush with the bottoms of the recesses, 65 dowel pins inserted in the ends of the tubes of the adjacent slabs for connecting the slabs together, and annular flanges on the pins received in the recesses of the adjacent slabs for maintaining the pins in place 70 and preventing them from sliding into one of the slabs, thereby disconnecting the adjacent slab.

In testimony whereof I affix my signature, in the presence of two witnesses.

CLEMENT C. McDONALD.
